UNITED STATES PATENT OFFICE.

HORACE E. WHITNEY, OF CAMBRIDGE, MASSACHUSETTS, ASSIGNOR TO DOVER STAMPING AND MANUFACTURING COMPANY, OF PORTLAND, MAINE, A CORPORATION OF MAINE.

LAMP-CONTAINER.

1,226,733.

Specification of Letters Patent. Patented May 22, 1917.

Application filed May 25, 1915. Serial No. 30,426.

To all whom it may concern:

Be it known that I, HORACE E. WHITNEY, of Cambridge, in the county of Middlesex and State of Massachusetts, a citizen of the 5 United States, have invented a new and useful Improvement in Lamp-Containers, of which the following is a specification.

My invention relates to a device for carrying spare electric lamps, especially designed 10 for use in respect to lamps for head lights of automobiles.

The essential object of the invention is to provide a reasonably small, compact and inexpensive receptacle in which the lamps can 15 be safely carried without danger of breakage when being transported.

My invention can best be seen and understood by reference to the drawings in which it is shown in its preferred form.

20 Figure 1 is a view in section of the device with the covers on and the lamps in place.

Fig. 2 is a view of a cover with a lamp inserted therein.

Fig. 3 is a view in part of the device showing a cover in place.

A is a hollow, cylindrical tube having covers B for each end. The covers B are constructed with bayonet grooves b of ordinary form, a being pins located on the outer side of the tube so that when the covers are placed upon the tube and slightly revolved, they will be locked against longitudinal displacement. Each cover B has a cylindrical socket C attached by electric welding or otherwise to its inside face, of a diameter large enough to receive the neck-piece of an electric lamp of the type desired to be carried. Within the socket C is a spring c one end of which is attached to the inner face of the cover at c¹, the other end c² being free to bear against the neck-piece d of the lamp D. The socket C also has slotted bayonet joints c³ at opposite sides, d¹ being the pins on the neck-piece of the lamp. The inner end of

the bayonet joint c³ is constructed to form 45 a depression c⁴. Upon the insertion of the neck-piece of the lamp within the socket C, the pin d¹ of the bayonet joint fitting in the slot c³ of the joint, the spring c will be depressed and upon a slight revolution of the 50 lamp the pin d¹ will enter the depression c⁴, whereupon the lamp will be securely locked in the socket C against accidental displacement.

The lamp being in place, the cover B is 55 then placed upon the tube A and locked as described, and the operation being repeated for the other cover, the lamps are then ready to be transported without chance of breakage.

To one using an automobile this device will be particularly useful, especially for purposes of touring, when it is desired to carry extra lamps safely and in as small a 60 space as possible.

Although I do not limit myself to the particular form or construction described, the form shown in the drawings is particularly advantageous for carriage in an ordinary tool box. I also do not limit myself to 70 automobile lamps, but the size may be changed for use with other types of lamps as desired. A feature of the invention is the very inexpensive cost of construction, for as I have designed the device it is made of 75 sheet tin.

What I claim as my invention is:—

An electric lamp container comprising a rigid tube having a cover removably attached to each end thereof, each cover having a socket containing a spiral spring and adapted to receive the neck piece of a lamp, means comprising a bayonet joint to hold said lamp in said socket, said spring being adapted to prevent said bayonet joint from 85 working loose when said container is in use.

HORACE E. WHITNEY.
